US00D974500S

(12) **United States Design Patent** (10) **Patent No.:** **US D974,500 S**
(45) **Date of Patent:** **** Jan. 3, 2023**

(54) **ROWING MACHINE**

(71) Applicant: **Hydrow, Inc.**, Cambridge, MA (US)

(72) Inventors: **Taehak Kwon**, Brookline, MA (US);
Julianna Miller, Boston, MA (US)

(73) Assignee: **Hydrow, Inc.**, Cambridge, MA (US)

(**) Term: **15 Years**

(21) Appl. No.: **29/831,358**

(22) Filed: **Mar. 18, 2022**

Related U.S. Application Data

(63) Continuation of application No. 29/750,571, filed on Sep. 15, 2020, which is a continuation of application No. 29/656,695, filed on Jul. 16, 2018, now Pat. No. Des. 898,843.

(57) **CLAIM**

The ornamental design for a rowing machine, as shown and described.

DESCRIPTION

FIG. 1 is a front perspective view of our rowing machine.

FIG. 2 is a front view of FIG. 1.

FIG. 3 is a back view of FIG. 1.

FIG. 4 is a right-side view of FIG. 1.

FIG. 5 is a left side view of FIG. 1.

FIG. 6 is a top view of FIG. 1.

FIG. 7 is a bottom view of FIG. 1; and,

FIG. 8 is a back-perspective view of FIG. 1.

The broken lines illustrate environmental features that form no part of the claimed design. Claimed surfaces are illustrated with shading lines.

1 Claim, 8 Drawing Sheets
